CIRCUIT BREAKER

Leonard B. Chubbuck, George R. Wishart, and
Kreston L. Ligaard Jeppesen, Hamilton, Ontario, Canada, assignors to Westinghouse Electric & Manufacturing Company, East Pittsburgh, Pa., a corporation of Pennsylvania

Application April 24, 1934, Serial No. 722,058

11 Claims. (Cl. 175—294)

Our invention relates generally to electrical apparatus and it has particular relation to circuit breakers which are used for opening and closing electrical power circuits.

5 The object of our invention, generally stated, is to provide a circuit breaker having a motor-operated closing mechanism which shall be simple and efficient in operation and which may be readily and economically manufactured and installed.

The principal object of our invention is to provide for connecting a motor to the movable contact members of a circuit breaker.

15 Another object of our invention is to provide a trip-free connection between a motor-operated closing mechanism and the movable contact members of a circuit breaker.

20 A further object of our invention is to provide for preventing the automatic reclosure of a circuit breaker after it has operated once, while the closing switch is held in the operated position.

25 A still further object of our invention is to provide for operating a circuit breaker by means of a motor and mechanically and electrically operated clutches connected in series between the motor and the movable contact members of the circuit breaker.

30 Other objects of our invention will in part be obvious and in part appear hereinafter.

Our invention accordingly is disclosed in the embodiment hereof shown in the accompanying drawings and comprises the features of construction, combination of elements, and arrangement 35 of parts which will be exemplified in the construction hereinafter set forth, and the scope of the application of which will be indicated in the appended claims.

40 For a more complete understanding of the nature and scope of our invention, reference may be had to the following detailed description, taken in connection with the accompanying drawings, in which:

45 Figure 1 is a view, partly in side elevation and partly in section, illustrating a concrete embodiment of our invention;

Fig. 2 is an enlarged view, partly in section, showing a part of the motor-operated mechanism;

50 Fig. 3 is a view, partly in side elevation and partly in section, taken along the line III—III of Fig. 4, showing details of construction of the motor-operated mechanism;

55 Fig. 4 is a sectional view taken along the line IV—IV of Fig. 3, and showing additional de-

tails of construction of the motor-operated mechanism; and

Fig. 5 is a diagrammatic view of the motor-operated mechanism and control circuits which may be used for controlling its operation. 5

Referring now particularly to Figs. 1 and 2 of the drawings, the reference character 10 designates generally a circuit breaker having fixed contact members 11 and 12 and a movable contact member 13 mounted within a suitable tank 14. Since the circuit breaker 10 constitutes no part of the invention, it will be understood that the particular embodiment thereof illustrated in the drawings is provided solely for the purpose of describing the invention more fully. 15

In order to operate the movable contact member 13 into engagement with the fixed contact members 11 and 12, a motor 15 is provided which may be of the polyphase squirrel-cage type. As illustrated, the motor 15 is mounted underneath 20 a connecting mechanism, shown generally at 16, the housing 17 of which may be mounted directly on the tank 14 by welding or otherwise. The motor 15 is provided with a drive shaft 18 extending into the connecting mechanism 16 25 where it is connected to a shaft 19 which is rotatably mounted therein, as will be more fully described hereinafter.

The lift rod 20, carrying the movable contact member 13, is connected to the hexagonal shaft 30 19, by means of a link 21, operating lever 22 comprising oppositely extending arms 23 and 24, link 25, and arm 26, which is secured to the shaft 19. As illustrated, the operating lever 22 is mounted for rotation on a shaft 27. It will 35 also be observed that a depending arm 28 is attached thereto and an accelerating spring 29 is connected between the arm 28 and a fixed pin 30 in order to more rapidly effect the opening of the contact members of the circuit breaker 10. 40

As will be set forth hereinafter, the arm 26 is caused to slightly overtravel after the contact members of the circuit breaker 10 are closed in order to provide for de-energizing the motor 15 45 after it is certain that the contact members have been closed and latched in this position. With a view to reducing the shock incident to the stopping of the connecting mechanism, a buffer spring 35 is provided and mounted on a suitable 50 bolt 36 which is slidably mounted, as illustrated, in a block 37.

In the event that it is desired to close the circuit breaker 10 manually, a handle (not shown) may be inserted in a socket 31 which 55

may be integrally formed with the upper arm 24 of the operating lever 22.

A tripping mechanism, shown generally at 38, is provided having a dashpot 39 of the customary type, for controlling the time of operation of the tripping device. The details of connection and operation of the tripping device 38 will be set forth hereinafter. It will be noted, however, that the tripping device 38 includes a tripping winding 40 surrounding an armature 41, Fig. 2.

In order to more clearly describe the invention, the connecting mechanism 16 in Fig. 1 has been illustrated with its parts in the position 15 which they assume when the contact members of the circuit breaker 10 are in the open position. In Fig. 2, the connecting mechanism 16 is illustrated in a position corresponding to the closed condition of the contact members of the circuit breaker 10.

With particular reference to Fig. 2 of the drawings, it will be observed that the upper operating arm 24 is provided with a short integrally formed lever arm 43 to which a connecting link 44 is attached for operating an auxiliary switch 45. The connecting link 44 is connected to a suitable operating arm 46 mounted on a shaft 47 of the auxiliary switch 45.

In order to open the circuits which are closed 30 for energizing the motor 15 after the contact members of the circuit breaker 10 have been moved to a predetermined position, a limit switch, shown generally at 50, is provided having a fixed contact member 51 and a movable contact member 52, the latter being pivoted in a suitable U-shaped frame 53 on a pin 54. It will be observed that the lower end of the movable contact member 52 is provided with a roller 55 which is disposed in the path of a cam 56 that is mounted on the shaft 19 and rotates therewith. A compression spring 57 is provided, as shown, for biasing the movable contact member 52 into engagement with the fixed contact member 51.

In the event that the circuit breaker 10 should be tripped immediately after the closing operation has been initiated, and after the limit switch 50 has been operated to the open position, it is desirable to maintain the limit switch 50 in the open position so that the circuit breaker 10 cannot automatically reclose to perform what is commonly known as a "pumping" action. Therefore, a holding winding 58 is provided which is arranged to be energized, as will be set forth hereinafter, upon energization of the motor 15. When the movable contact member 52 is operated to the open position by means of the cam 56, an armature 59 mounted on the upper end of the contact member 52 is moved into the magnetic field generated by the winding 58 so that the contact member 52 is held in the open position so long as the winding 58 is energized.

Referring now particularly to Figs. 3 and 4 of the drawings, a detailed description will be given of the connecting mechanism 16, which is provided for causing driving engagement between the shaft 18 driven by the motor 15 and the shaft 19 which is directly connected to the movable contact member 13 of the circuit breaker 10. For this connection, it is desirable to provide means whereby this connection may be accomplished with a minimum expenditure of energy and at the same time insuring that direct and positive connection will be maintained during the closing operation. It is also desirable to provide for breaking the connection between the

driving shaft 18 and the driven shaft 19 at any time while they are in driving engagement in order to prevent the contact members of the circuit breaker 10 from closing, for instance on a short circuit, or for any other reason, making it desirable to break the driving connection. It is also desirable to provide for connecting the motor 15 to operate the contact members of the circuit breaker 10 to the closed position from any last position of the motor 15. That is, the 10 rotor of the motor 15 and the mechanism connected directly thereto need not be in any particular position relative to the other parts of the device in order that the circuit breaker 10 may be operated.

With the foregoing conditions in mind, a clutch, shown generally at 65, is provided of the band friction type. The clutch 65 comprises a drum 66 which is mounted for rotation with the shaft 19. Surrounding the drum 66 is positioned 20 a helical clutch band 67, the upper end or high torque end, Fig. 4, of which is secured to a worm wheel 68 which is mounted for rotation around the drum 66. A worm 69 is mounted on the motor shaft 18 and in engagement with the worm 25 wheel 68 for driving it.

The clutch band 67 is provided in the form of a helix around the drum 66 with a slight clearance therebetween for gripping the drum 66 when the lower end or low-torque end, Fig. 4, is held 30 with respect to the drum 66. When a relatively slight force is applied to the low-torque end of the clutch band 67, it immediately grips the drum 66, thereby successively causing the succeeding turns of the clutch band 67 to engage the drum 35 66. Due to the frictional engagement between the succeeding turns of the clutch band 67 with the drum 66, only a relatively slight force is required to hold the band 67 in driving engagement with the drum 66, while a relatively large 40 torque may be transmitted from the worm wheel 68 to the drum 66.

Since only a relatively slight torque need be applied at the low-torque end of the clutch band 45 67, the cross-sectional area of the turns may be gradually diminished, as illustrated, from the high-torque end to the low-torque end, as will be readily understood.

In order to provide the slight torque which is required for operating the clutch 65, an electro- 50 magnetic clutch, shown generally at 73, of the face plate type is provided. The face plate 74 is secured to the low-torque end of the clutch band 67 and mounted for rotation around the shaft 19 through the provision of a suitable bush- 55 ing 75. The electro-magnetic clutch 73 also comprises a winding-housing clutch plate 76 which is mounted for rotation with the shaft 19, and carries a winding 77 in a suitably recessed opening in the face.

It will be observed that, as long as the winding 77 remains de-energized, the face plate 74 will be free to rotate around the shaft 19, together with the clutch band 67 and the worm wheel 68, as driven by the worm 69. However, as soon as the winding 77 is energized, further relative movement of the face plate 74 with respect to the shaft 19 is arrested, thereby causing the low-torque end of the clutch band 67 to engage the drum 66 with the result that the remaining turns 70 of the clutch band 67 are brought into frictional engagement with the drum 66 and causing the shaft 19 to be rotated to operate the circuit breaker 10 to the closed position.

In order to hold the contact members of the 75

circuit breaker 10 in the closed position, a latch 80 pivotally mounted on a suitable shaft 81 is provided having a recessed portion 82 disposed to engage a roller 83, which is carried by the plate 76, of the electro-magnetic clutch 73. A coil spring 84 is provided for biasing the latch 80 into engagement with the roller 83. Since the roller 83, which is caused to engage the latch 80, is mounted on the clutch plate 76, which in turn is fixed on the shaft 19 for rotation therewith, it will be understood that the movable contact member 13 of the circuit breaker 10 will be held in engagement with the fixed contact members 11 and 12, since the shaft 19 is directly connected to the lift rod 20 through the lever arrangement, which has been previously described.

With a view to tripping the circuit breaker 10 to the open position, a latch arm 85 is secured to the shaft 81 so that movement thereof causes a corresponding movement of the latch 80. As illustrated, the latch arm 85 extends inwardly underneath the band friction clutch 65 and into the path of movement of a cross piece 86 carried by a cradle member 87, which is pivotally mounted about a shaft 88. The cradle member 87 is provided with an additional cross-piece 89, which is positioned in the path of movement of the armature 41. It will be understood, therefore, that the cradle member 87 will be moved in a clockwise direction on energization of the tripping winding 40, thereby causing the latch arm 85 and latch 80 to be moved in a counter-clockwise direction, and removing the recessed portion 82 of the latch 80 from engagement with the roller 83 and permitting the contact member 13 of the circuit breaker 10 to be moved to the open position under the combined influence of the forces of gravity and the accelerating spring 29.

It will be understood that additional tripping mechanisms 38 may be provided having additional armatures 41 for engaging the cross-piece 89 of the cradle member 87 in the event that it is desirable to control the tripping of the circuit breaker 10 in response to other conditions not set forth in this specification, as will be readily understood.

Referring now particularly to the diagram illustrated in Fig. 5 of the drawings, it will be observed that the circuit breaker 10 is provided for connecting sections of power conductors 91, 92 and 93 together. It will be also observed that a switch, as shown generally at 94, is provided for connecting the windings of the motor 15 to the conductors 91, 92 and 93. While the main power circuit may be used to supply current for operating the motor 15, it will be readily understood that any other suitable source of power may also be used.

A protective relay, shown generally at 95, is provided having an energizing winding 96 arranged to be energized from the secondary winding 97 of a current transformer. While the protective relay 95 is illustrated as being responsive to current flow in the power conductors, it will be readily apparent that its operation may be controlled in response to any other variable factor in the transmission system, as may be desired.

A rectifier 98 of the copper-oxide type may be provided for supplying direct-current for energizing the winding 77 of the electro-magnetic clutch 73.

In operation, assuming that it is desired to close the circuit breaker 10, the close switch 101 is

depressed, thereby energizing the winding 77 of the electro-magnetic clutch 73 and winding 109 of the switch 94 through the rectifier 98.

The circuit for energizing the winding 77 of the electro-magnetic clutch 73 may be traced from the energized conductor 91 through conductor 102, contact members 103 of the closed switch 101, conductor 104, contact members 105 of the protective relay 95, which are normally closed, conductor 106, contact members 51 and 52 of the limit switch 50, conductor 107, rectifier 98 and conductor 108 to energized conductor 92. The circuit connections between the winding 77 and the rectifier 98 are obvious.

It will be observed that the winding 109 of the switch 94 is connected in parallel circuit relation with the rectifier 98, and, therefore, it is unnecessary to trace the circuit whereby it is energized.

As soon as the switch 94 is operated to the closed position, the windings of the motor 15 are energized, thereby causing it to rotate the shaft 18. The winding 77 of the electro-magnetic clutch 73 being energized, the band friction clutch is operated to directly connect the shaft 18 to the shaft 19, and as a result the circuit breaker 10 is operated to the closed position.

When the circuit breaker 10 is in the fully closed position, the slight overtravel permitted by the linkage between the shaft 19 and the lift rod 20 is sufficient to permit the cam 56 to engage the roller 55, thereby causing the contact members 51 and 52 of the limit switch 50 to be opened against the force of the biasing spring 51. These contact members are held in the open position by means of the winding 58, which is energized on the operation of the closed switch 101 over an obvious circuit.

As soon as the circuit breaker 10 has been closed, the switch 101 may be released. This action, however, only de-energizes the winding 58, the motor 15 and the winding 77 of the electro-magnetic clutch having been de-energized through the opening of contact members 51 and 52, as will be readily understood.

In the event that a short circuit should exist on any of the conductors 91, 92 or 93, causing a flow of current in the winding 96 of the protective relay 95 beyond a predetermined amount, the contact members 105 thereof will be opened and contact members 110 will be closed. The opening of contact members 105 immediately causes the de-energization of both the motor 15 and the winding 77 of the electro-magnetic clutch 73 provided they are energized, thereby permitting the contact members of the circuit breaker 10 to be immediately operated to the open position. This then provides what is known as "trip free" operation.

If the circuit breaker 10 has been completely closed and latched before the occurrence of the fault, the closure of the contact members 110 completes a circuit for energizing winding 40 of the tripping device 38, thereby releasing the latch 80 from engagement with the plate 76 of the electro-magnetic clutch 73 and permitting the circuit breaker 10 to be opened, as will be readily understood.

The circuit for energizing tripping winding 40 may be traced from energized conductor 91, through conductors 102 and 111, contact members 110 of the protective relay 95, conductors 112 and 113, winding 40, conductor 114, contact members 115 of the auxiliary switch 45, and conductors 116 and 108 to energized conductor 92.

In the event that it is desired to manually

trip the circuit breaker 10, the trip switch 117 may be operated. Since the contact members 118 of the trip switch 117 are connected in parallel circuit relation with the contact members 110 5 of the protective relay 95, it is unnecessary to trace again the circuit for energizing the tripping winding 40 on operation of the trip switch 117.

Since certain further changes may be made in the above construction, and different embodiments of the invention may be made without departing from the scope thereof, it is intended that all matter contained in the above description or shown in the accompanying drawings shall be interpreted as illustrative and not in a 15 limiting sense.

We claim as our invention:

1. A circuit interrupter comprising, in combination, relatively movable contact members disposed to open and close an electrical circuit, a 20 motor for operating said contact members to the closed position, a band friction clutch interposed between said contact members and said motor, and an electro-magnetic clutch disposed to effect the operation of said band friction clutch to provide driving connection between said motor and said contact members.

2. A circuit interrupter comprising, in combination, relatively movable contact members disposed to open and close an electrical circuit, a 30 motor for operating said contact members to the closed position, a band friction clutch interposed between said contact members and said motor, a latch disposed to automatically hold said contact members in the closed position, and an electro- 35 magnetic clutch disposed to effect the operation of said band friction clutch to provide driving connection between said motor and said contact members.

3. A circuit interrupter comprising, in combination, relatively movable contact members disposed to open and close an electrical circuit, a motor for operating said contact members to the closed position, contact means for controlling the operation of said motor, a closing mechanism connected directly to said contact members and disposed to provide a slight overtravel for operating said contact means to deenergize said motor on closure of said contact members, a band friction clutch interposed between said closing mechanism and said motor, a latch disposed to automatically engage with said closing mechanism during said overtravel period, and an electro- 50 magnetic clutch disposed to effect the operation of said band friction clutch to provide driving connection between said motor and said closing mechanism.

4. A circuit interrupter comprising, in combination, relatively movable contact members disposed to open and close an electrical circuit, a 60 motor for operating said contact members to the closed position, and a band friction clutch and an electro-magnetic clutch disposed in series relation between said contact members and said motor to effect driving connection therebetween.

5. A circuit interrupter comprising, in combination, relatively movable contact members disposed to open and close an electrical circuit, a motor, and a band friction clutch and an electro- 65 magnetic clutch disposed in series relation between said contact members and said motor for effecting driving connection therebetween to operate said contact members to the closed position, said electro-magnetic clutch being disposed at 70 the low-torque end of said band friction clutch

whereby only a relatively small force is required to effect said driving connection.

6. A circuit interrupter comprising, in combination, relatively movable contact members disposed to open and close an electrical circuit, a 5 motor, a band friction clutch comprising a drum directly connected to said contact members and a helical band disposed around said drum and having the high-torque end directly connected to said motor, and an electro-magnetic clutch disposed between the low-torque end of said band and said drum for effecting driving connection therebetween, thereby permitting said motor to operate said contact members to the closed position. 15

7. A circuit interrupter comprising, in combination, relatively movable contact members disposed to open and close an electrical circuit, a motor, a band friction clutch interposed between said contact members and said motor, an electro- 20 magnetic clutch of the face plate type disposed to effect the operation of said band friction clutch to provide driving connection between said motor and said contact members for operating them to the closed position regardless of the last position of the motor, and circuit means for connecting said motor and said electro-magnetic clutch to a source of electric power. 25

8. A circuit interrupter comprising, in combination, relatively movable contact members disposed to open and close an electrical power circuit, a motor for operating said contact members to the closed position, a band friction clutch interposed between said contact members and said motor, an electro-magnetic clutch disposed to 30 effect the operation of said band friction clutch to provide driving connection between said motor and said contact members, circuit means for connecting said motor and said electro-magnetic clutch to a current source, and relay means connected to be responsive to the occurrence of a 35 fault in said power circuit for deenergizing said electro-magnetic clutch, thereby substantially instantaneously disconnecting said contact members from said motor. 45

9. A circuit interrupter comprising, in combination, relatively movable contact members disposed to open and close an electrical power circuit, a motor for operating said contact members to the closed position, a band friction clutch 50 interposed between said contact members and said motor, an electro-magnetic clutch disposed to effect the operation of said band friction clutch to provide driving connection between said motor and said contact members, circuit means for connecting said motor and said electro-magnetic clutch to a current source, a latch disposed to automatically hold said contact members in the closed position, electrical means for tripping said latch to release said contact members for movement to the open position, and relay means connected to be responsive to the occurrence of a fault in said power circuit for simultaneously deenergizing said electro-magnetic clutch, thereby substantially instantaneously disconnecting said 55 contact members from said motor in the event said electro-magnetic clutch is not already deenergized, and energizing said electrical means for tripping said latch in the event said latch has operated to hold said contact members in 70 the closed position.

10. A circuit interrupter comprising, in combination, relatively movable main contact members disposed to open and close an electrical circuit, a motor for operating said contact members 75

to the closed position, a band friction clutch interposed between said main contact members and said motor, an electro-magnetic clutch disposed to effect the operation of said band friction clutch to provide driving connection between said motor and said main contact members, circuit means for connecting said motor and said electro-magnetic clutch to a source of electrical energy, a switch for controlling the operation 10 of said circuit means to energize said motor and clutch on closure thereof and anti-pumping means operable when said contact members have been operated to a predetermined position for preventing a second closure thereof until said 15 switch is released and again closed.

11. A circuit interrupter comprising, in combination, relatively movable main contact members disposed to open and close an electrical circuit, a motor for operating said contact members to the closed position, a band friction clutch interposed between said main contact members and said motor, an electro-magnetic clutch dis-

posed to effect the operation of said band friction clutch to provide driving connection between said motor and said main contact members, circuit means for connecting said motor and said electro-magnetic clutch to a source of electrical 5 energy, a switch for controlling the operation of said circuit means to energize said motor and clutch on closure thereof, and anti-pumping means comprising normally closed auxiliary contact members connected in series circuit relation 10 with said circuit means and disposed to be opened when the main contact members of the circuit interrupter are moved to a predetermined position, thereby opening the energizing circuit for said motor and said clutch, and a holding winding disposed to be energized on closure of said switch for maintaining said auxiliary contact members in the open position as long as said switch remains in the closed position.
